UNITED STATES PATENT OFFICE.

JAMES VRBA, OF MARSHALLTOWN, IOWA, ASSIGNOR TO LENNOX FURNACE COMPANY,
OF MARSHALLTOWN, IOWA.

CONNECTING COLLAR FOR FURNACES.

Application filed November 24, 1924. Serial No. 751,962.

To all whom it may concern:

Be it known that I, JAMES VRBA, a citizen of the United States, and a resident of Marshalltown, in the county of Marshall and 5 State of Iowa, have invented a certain new and useful Connecting Collar for Furnaces, of which the following is a specification.

In the construction of hot air furnaces, it is customary to have a heat or combustion 10 chamber and also a radiating drum slightly spaced apart from the heating chamber in the rear thereof and within the furnace casing, and in such construction there is customarily provided a so-called connecting 15 collar through which the products of combustion from the heating chamber may pass to the radiating drum and from there to the chimney. In the construction of steel furnaces, these connecting collars are usually 20 made of cast metal and must be connected to both the heating chamber and the radiating drum in a strong, durable and air-tight manner, and they are usually made in two 25 parts so that the radiating drum with its part of the connecting collar may be detached. Heretofore great difficulty has been experienced in providing suitable connection between the part of the connecting collar attached to the radiating drum and that 30 part that is attached to the heating chamber, and various expedients have been provided for this purpose.

The object of my invention is to provide 35 an improved connecting collar of simple, durable and inexpensive construction that may be readily, quickly and easily made of cast iron by the ordinary moulding process, and in which the radiating drum with its 40 collar member may be readily, quickly and easily attached to that part of the connecting collar applied to the heating chamber, and there firmly and immovably held in proper position without the use of bolts, screws or other fastening devices; and also 45 in this connection to provide a form of joint or connection between the two collar members to which cement or other packing ma-

terial may be readily and easily applied to form a substantially air-tight joint.

My invention consists in the construction, 50 arrangement and combination of the various parts of the device, whereby the objects contemplated are attained, as hereinafter more fully set forth, pointed out in my claims, and illustrated in my accompanying 55 drawings, in which:

Figure 1 shows a perspective view illustrating a portion of the heating chamber and a portion of a radiating drum connected together by means of my improved connecting 60 collar.

Figure 2 shows an enlarged sectional view on the line 2—2 of Figure 1.

Figure 3 shows a vertical sectional view taken on the line 3—3 of Figure 1, showing 65 the collar member that is attached to the heating chamber in section, and the collar member that is attached to the radiating drum in front elevation.

Figure 4 shows a vertical sectional view 70 on the line 4—4 of Figure 3, illustrating the collar member for the radiating drum and omitting the collar member for the heating chamber; and

Figure 5 shows a perspective view illustrating the collar member for the heating chamber. 75

Referring to the accompanying drawings, I have used the reference numeral 10 to indicate the heating chamber and 11 the radiating drum. The connecting collar is made in two parts, each formed of a single casting. That part of the connecting collar which is to be connected to the heating chamber comprises a flange 12 shaped to surround an opening formed in the upper rear end of the heating chamber and provided with rivet openings by which it may be secured to the heating chamber. 80 85

Extended rearwardly from the flange 12 90 is the collar member 13. At the bottom of the member 13 there is a flange projected rearwardly indicated by the numeral 14, and tapered on its upper surface down-

wardly and rearwardly, and its upper edge is inclined from the rear upwardly and toward the heating chamber at 15. The upper portion of the part 13 and the sides thereof are formed with a shoulder at 16, and projecting rearwardly from this shoulder is a flange 17, the top of which is inclined downwardly and rearwardly, and its sides are inclined rearwardly and toward each other, the latter inclination being clearly shown in Figure 2, and, as will be seen by referring to Figure 5, the flange 14 projects rearwardly further than the flange 17.

Formed on the side walls of the member 13 are the locking wedges 18. These wedges, as will be seen, are spaced apart forwardly from the shoulder 16 and are preferably cast integral with the member 13.

The collar member that is attached to the radiating drum comprises a flange 19 provided with rivet openings and designed to be riveted to the front upper portion of the radiating drum surrounding an opening therein. At its bottom portion there is a forwardly extended flange 20 to be received into the flange 14, and at the base of this flange 20 there is a shoulder 21 designed to engage the rear edge of the part 14. At its sides above the flange 20 there is a shoulder 22 shaped and inclined to rest upon the inclined shoulder 15. At the top of the collar member for the radiating drum there is a flange 23 designed to rest on top and fit against the inclined flange 17 and against the shoulder 16, and at the base of this flange 23 at the top there is a shoulder 24 against which the rear edge of the flange 17 engages.

At the sides of the radiating drum there are two wedge lock devices, each comprising a forwardly extended flange 25 and an inwardly extended flange 26, thus forming a recess to receive the wedge lock member 18, the top of the wedge lock member being closed at 27, as shown in Figure 4. The entire body of this wedge lock member on the radiating drum collar member projects forwardly beyond the flanges 23, as shown in Figure 4.

In practical operation, it is obvious that the entire connecting collar may be readily and easily cast in two parts with the use of simple patterns in the ordinary manner. Each part is then permanently connected by rivets or bolts to the corresponding part of the furnace. Then a cement or packing material is placed upon the upper surface of the flange member 14 and on the upper surface of the flange member 17, and upon the outer sides of the flange member 17, then the radiating drum with its connecting member attached thereto is placed in position with the connecting member thereon just above the connecting member on the heating chamber. It is then moved downwardly with the wedge lock members 18 in-

serted in the wedge lock members 25, and when the radiating drum has been moved downwardly to its limit of movement, the flange 20 will engage and fit against the upper beveled surface of the flange 14, and the flange 23 will engage and rest upon the beveled surface of the flange member 17. During this downward movement, the wedge lock members 18 will serve to draw the two connecting collar members toward each other, thus causing the tapered flanges to slide upon each other and upon the cement or packing material inserted between them until a gas and air-tight fit is made. Further downward movement is then limited by the shoulders 22 engaging the shoulders 15, all of which may obviously be done very quickly and there is no need of any bolts, rivets or similar fastening devices. Furthermore, the parts are held together in such manner that the radiating drum cannot move in any direction relative to the heating chambers.

In this connection, I obtain a very marked advantage by having the wedge lock devices entirely spaced apart from the tapered flanges, because if the wedge lock devices were applied at the surfaces of the tapered flanges, it would be difficult to obtain smooth castings; and furthermore, it would be almost impossible to properly apply cement or other packing material completely surrounding the joint between the two connecting members, as such wedge lock devices would interfere with the packing or cement.

I claim as my invention:

1. A connecting collar of the class described, comprising in combination two collar members formed with coacting tapered flanges, said collar members being also formed with coacting wedge lock devices applied thereto at points spaced apart from said tapered flanges.

2. A connecting collar of the class described, comprising a collar member formed with a rearwardly extended flange at its bottom and the lower portion of said flange having its upper surface and the inner surface of its sides inclined toward the rear, said collar also being formed with a flange at its top and the upper portions of its side having the outer surface thereof inclined downwardly and rearwardly, the lower flange being projected rearwardly to a greater distance than the upper flange, and there being a shoulder formed between them, and wedge devices formed integral with a flange at the sides thereof and spaced forwardly from said upper flange member, and a coacting collar member having at its top and the upper portion of its sides a forwardly extended flange with its lower edge inclined forwardly and upwardly, and the edges of its sides inclined forwardly and outwardly, and also having at the bottom

and lower portion of its sides a flange with its bottom inclined forwardly and upwardly, and the adjacent portions of its sides inclined forwardly and inwardly, there being 5 shoulders at the intersection of said flanges, said upper flange being projected forwardly to a greater extent than the lower flange, and wedge lock devices at the sides of the

collar member projected forwardly beyond the upper flange member and being designed 10 to receive the wedge lock devices on the other collar member, substantially as set forth and for the purposes stated.

Des Moines, Iowa, November 1, 1924.

JAMES VRBA.
